United States Patent Office

Des. 198,988
Patented Aug. 25, 1964

198,988

TICKET ISSUING MACHINE OR SIMILAR ARTICLE

Albert Hohmann, Brooklyn, N.Y., assignor to Taller &
Cooper, Inc., Brooklyn, N.Y., a corporation of New
York

Filed Apr. 2, 1964, Ser. No. 79,316

Term of patent 14 years

(Cl. D52—2)

FIG. 1

FIG. 2

FIG. 5

FIG. 4

FIG. 3

FIGURE 1 is a top plan view of a ticket issuing machine showing my new design;

FIGURE 2 is a front elevational view thereof;

FIGURE 3 is a side elevational view as viewed from the left of FIGURE 2;

FIGURE 4 is a side elevational view as viewed from the right of FIGURE 2; and

FIGURE 5 is a rear elevational view thereof.

I claim:

The ornamental design for a ticket issuing machine or similar article, substantially as shown.
